ORGAN VALVE

Filed July 26, 1926

UNITED STATES PATENT OFFICE.

EDMOND VERLINDEN, OF MILWAUKEE, WISCONSIN.

ORGAN VALVE.

Application filed July 26, 1926. Serial No. 124,978.

The invention relates to organ valves, more particularly for use with treble chests, but capable of application to other organ chests.

An object of the invention is to provide 5 an organ valve construction which will avoid improper actuation of air-pressure-operated devices incident to the leakage of air to the conduits leading to such devices.

Another object of the invention is to provide 10 vide an electro-magnetic organ valve which is prompt in action and is of simple, durable and inexpensive construction.

A further object of the invention is the provision of an electro-magnetic organ valve 15 which can be mounted and assembled in a simple manner and which is readily accessible for the purpose of wiring, inspection, repairs and replacements.

The invention further consists in the 20 several features hereinafter set forth and more particularly defined by the annexed claims.

In the accompanying drawings:

Fig. 1 is a transverse sectional elevation 25 through a treble chest embodying the organ valve construction of this invention;

Fig. 2 is a fragmentary plan view thereof with the pipes removed, parts being broken away and parts being shown in section;

Fig. 3 is a bottom plan view of one of the 30 valve casings; and

Fig. 4 is a fragmentary sectional elevation of a modified form of valve.

In these drawings, 10 designates a treble chest having a longitudinally extending air 25 channel 11 supplied with air under pressure. The chest includes an apertured member 12 disposed above the channel 11 and preferably provided with a facing 13 of leather or other suitable material on its upper surface.

A pipe-supporting strip 14 is secured longitudinally along one edge of the member 12 and carries a series of organ pipes 15, each 40 communicating with an upright passage 16 extending through the strip.

A series of upright air passages 17 extends 45 through the member 12 in communication with the subjacent air channel 11, there being an air passage 17 for each pipe 15. Each air passage 17 is closed at its upper end by a 50 valve casing 18 secured to the upper face of the member 12 by screws 19. Each valve casing is provided with a recess 20 in its bottom face registering with the air passage 17 and including an enlarged portion 21 laterally offset with respect to the air passage 55

17 to confine therein for limited vertical movement a disk valve 22, which, in the present instance, includes magnetizable material to form an armature. In accordance 60 with common practice the disk valve is faced with leather, paper or other suitable material to insure good seating and to avoid sticking and sluggish action. The valve casing 18 is attached permanently to an upright electro-magnet 23, the pole pieces 24 of which are embedded in the valve casing and have their lower ends projecting below the upper face of the recess or cavity 20, where they are preferably surrounded by bosses 25. 70

Each disk valve 22 is adapted to seat over one end of an air passage 26, the other end of which opens into a recess 27 in the member 12 registering with the air passage 16 communicating with the pipe 15. A venting 75 port or passage 28 is also formed in the strip 14 in communication with the recess 27 and is preferably, though not necessarily, of somewhat larger cross-sectional area than that of the pipe 15. The venting passage 80 28 preferably includes a laterally extending portion opening at the side edge of the strip 14 in order to avoid settling of foreign matter through the passage and into the recess 27.

Each recess 27 is preferably of the general key-hole shape seen in Fig. 2 in order to present confining walls for a horizontally disposed disk valve 29, which is mounted for limited vertical movement within the recess to close either the outer end of the air passage 26, as seen in Fig. 1, or the inner end 90 of the venting passage 28, as hereinafter described. For this purpose, the adjacent ends of the passages 26 and 28 are in substantial alignment.

In the modified form of electro-magnetic valve shown in Fig. 4 the valve casing 18' encloses a recess 20' formed in the member 12 and in communication with the air passage 17. The recess 20' may be of the same 100 general shape as that of the recess 27, in order to confine therein for limited movement a disk valve 22, which also forms an armature co-operating with an electro-magnet 23 having its pole pieces 24 embedded in the valve casing.

The disk valves 22 normally rest against their seats to close communication between the air passages 17 containing air under pressure and the air passages 26 leading to 110 the pipes. The seating of the valves is

rendered firm by the pressure of the air above them. When it is desired to have a pipe speak the corresponding electromagnet 23 is energized, thereby lifting the disk valve 22 and admitting air under pressure from the recess 20 into the passage 26. The disk valve 29 at the outer end of this passage will then be lifted by air pressure into seating engagement with the bottom face of the strip 14 and closing the inner end of the venting passage 28, thereby permitting the flow of air under pressure into the recess 27, through the passage 16 and thence into the pipe, causing it to speak. Under such conditions the air pressure in the recess 27 will hold the disk valve 29 firmly against its upper seat to close the venting passage 28, so that the full air pressure supplied is available for the pipe. As soon as the magnet 23 is de-energized the disk valve 22 will drop to close the air passage 26 with respect to the recess 20, and the disk valve 29 will drop immediately thereafter to open the venting passage 28 with respect to the recess 27.

In order to insure the prompt dropping of the disk valve 22 from its upper position when the magnet 23 is de-energized, a substantial area of the upper surface of the valve is also subject to air pressure by reason of the pole pieces 24 and bosses 25 projecting below the upper surface of the recess 20, thus largely counteracting the pressure of air on the bottom surface of the valve when the valve is unseated.

In the case of the smaller organ pipes it will be appreciated that air under relatively low pressure is sufficient to cause them to speak and that ciphering can be easily caused by small particles of sawdust or other foreign matter obstructing the complete closing of the valves. This condition has heretofore necessitated the inconvenience of adjusting or dismantling in order to restore normal operation. In the organ valve construction of the present invention the possibility of ciphering is obviated by providing the venting passage 28, which is preferably of substantially larger area than that of the organ pipe, so that any leakage into the passage 26 will pass the disk valve 29 by lifting it slightly and be dissipated through the venting passage, thus preventing the accumulation of sufficient pressure to sound the pipe. Under the application of the lowest normal air pressure to the passage 26 the disk valve 29 will close the venting passage 28 to permit functioning of the pipe in the normal manner. By seating the valve 29 over the outlet end of the passage 26, the lifting of the valve to close the venting passage will be facilitated and insured.

It will be seen that the venting means is operated directly by the air blast to the pipe and does not require a mechanical ac-

tuating connection with a valve membrane or pneumatic. This greatly simplifies construction and design, facilitates assembly and lessens cost of manufacture. The venting means insures a prompt cessation of the speaking of the pipes and permits good staccato playing. While the venting means is more particularly intended for use with the pipes on stops of an organ, it will be apparent that it is of value in preventing the improper actuation of other air-pressure-operated devices found in organ construction.

The valve casing 18 and electromagnet 23 are both exterior to the chest, which facilitates wiring and mounting and provides good accessibility for inspection and repairs.

What I claim as new and desire to secure by Letters Patent is:

1. In an organ valve, the combination, with a pipe, of valve means for controlling the admission of air to said pipe, venting means for relieving said pipe from low pressure air leakage, and means operated directly by the blast of air to said pipe for rendering said venting means inoperative during the application of operative air pressure to said pipe.

2. In an organ valve, the combination, with a pipe, of a chamber in communication with said pipe and having a venting port, means for controlling the admission of air under pressure to said chamber, and a valve in said chamber movable by air pressure thereagainst to close said venting port from said chamber upon the admission of air under pressure to said chamber and movable to expose said port to said chamber upon the absence of operative air pressure.

3. In an organ valve, the combination, with a pipe, of a chamber in communication with said pipe and having a venting port, means including an air passage in communication with said chamber for conducting thereto air under pressure, and a valve in said chamber normally disposed over the outlet end of said air passage to permit communication between said venting port and chamber and movable by air pressure thereagainst to close said venting port with respect to said chamber upon the flow of air under operative pressure from said air passage into said chamber.

4. In an organ valve, the combination, with a pipe, of a chamber in communication with said pipe and having a venting port at one side, air admission means including an air passage in communication with said chamber at the opposite side in alignment with said venting port, and a disk valve mounted within said chamber in register with said air passage and movable under the application of operative air pressure

against said valve to close said venting port with respect to said chamber.

5. In an organ valve, the combination, with a pipe, of venting means including a 5 by-pass port in communication with and larger than said pipe to prevent said pipe from speaking at less than operative air pressure, and means operated directly by the blast of air to said pipe for closing said 10 by-pass port during the application of operative air pressure to said pipe.

6. In an organ valve, the combination of a valve casing forming walls of an air chamber having inlet and outlet ports, an electromagnet carried by said casing, a disk valve 15 normally closing said outlet port with respect to said chamber and attracted by said electromagnet to open said port, and stop means engageable with a relatively 20 small area of said disk when said disk is attracted to permit the access of air in said chamber behind said disk.

7. In an organ valve, the combination of a valve casing forming walls of a chamber 25 having inlet and outlet ports, an electromagnet carried by said casing and having its polar ends secured therein, said valve casing having projecting bosses in said chamber around said polar ends, and a disk valve 30 seated in said casing and normally closing said outlet port and attracted by said electromagnet to open said port, said projecting bosses forming a space behind the attracted 35 valve to permit the access thereto of air in said chamber.

8. In an organ valve, the combination of a valve casing forming walls of a chamber, a member forming other walls of said chamber and having inlet and outlet ports therein 40 communicating with said chamber, an electromagnet carried by said valve casing and having its polar ends projecting from the inner surface of said casing to form a space about said ends, and a disk valve in said chamber 45 normally closing said outlet port and attracted by said electromagnet to open said port, the space about said polar ends permitting the access of air behind said disk 50 valve when it is attracted by said electromagnet.

9. In an organ valve, the combination of a valve casing forming walls of a chamber having inlet and outlet ports, an electromagnet carried by said valve casing and having its polar ends projecting from the inner 55 surface of said casing to form a space about said ends, and a disk valve in said chamber normally closing said outlet port and attracted by said electromagnet to open said 60 port, said space about said polar ends permitting the access of air behind said disk valve when it is attracted by said electromagnet.

10. In an organ valve, the combination 65 of a chest having a port, a disk valve nor-

mally closing said port, a valve casing secured to said chest and forming walls of a chamber enclosing said valve, means for admitting air to said chamber at a pressure higher than that normally existing in said 70 port, and an electromagnet carried by said casing and exterior to said chest for attracting said valve to open said port with respect to said chamber.

11. In an organ valve, the combination 75 of a chest having a port opening at its outer surface, a disk valve normally resting on said surface to close said port, a valve casing secured to said chest and forming walls of a chamber enclosing said valve, means for 80 admitting air to said chamber at a pressure higher than that normally existing in said port, and an electromagnet carried by said casing and exterior to said chest for attracting said valve to open said port with 85 respect to said chamber.

12. In an organ valve, the combination of a member having inlet and outlet ports therein, a valve casing secured to said member for enclosing the ends of said ports and 90 having a chamber permitting communication between said ports, an electro-magnet exterior to said ported member and having polar portions secured to said casing, and a disk valve in said chamber normally seating against said ported member to close said 95 outlet port and being attractable by said electro-magnet to open said port for effecting communication between said ports.

13. In an organ valve, the combination of 100 a member having inlet and outlet ports therein and forming walls of a chamber permitting communication between the ends of said ports, a valve casing secured to said member and forming other walls of said 105 chamber, an electro-magnet exterior to said ported member and having polar portions secured to said casing, and a disk valve in said chamber normally seating against said ported member to close said outlet port and 110 being attractable by said electro-magnet to open said port for effecting communication between said ports.

14. In an organ valve, the combination of 115 a chest having an inlet port and an outlet port both opening at the outer surface of said chest in adjacent relation, a disk valve normally resting on said surface to close said outlet port, a valve casing secured to said chest and forming walls of a chamber 120 enclosing said valve and the ends of said ports, and an electro-magnet exterior to said chest and having polar portions carried by said casing for attracting said valve to open said outlet port with respect to said chamber. 125

15. In an organ valve, the combination, with means to be actuated by air under pressure, of valve means for controlling the admission of air to said air-pressure-operated means, venting means for relieving said 130

air-pressure-operated means from air pressure incident to leakage past said valve means, and means operated by the flow of air under pressure to said air-pressure-operated means for rendering said venting means inoperative during the application of operative air pressure to said air-pressure-operated means.

16. In an organ valve, the combination of
10 a valve casing forming walls of an air chamber having inlet and outlet ports, an electro-

magnet carried by said casing, a disk valve normally closing said outlet port with respect to said chamber and attracted by said electro-magnet to open said port, and means 15 for limiting the displacement of said valve when attracted by said electro-magnet to permit the access of air in said chamber against the surface of said valve adjacent the electro-magnet.

20 In testimony whereof, I affix my signature.
EDMOND VERLINDEN.
